UNITED STATES PATENT OFFICE

123,091

DESIGN FOR A COMBINATION STAND FOR SMOKERS

Charles Rizzuto, Brooklyn, N. Y.

Application June 4, 1940, Serial No. 92,812

Term of patent 7 years

To all whom it may concern:

Be it known that I, Charles Rizzuto, a citizen of the United States of America, residing at Brooklyn, in the county of Kings and State of New York, have invented a new, original, and ornamental Design for a Combination Stand for Smokers, of which the following is a specification, reference being had to the accompanying drawing, forming a part thereof.

In the drawing:

The figure is a perspective view of the combination stand for smokers, showing my new design.

I claim:

The ornamental design for a combination stand for smokers, as shown.

CHARLES RIZZUTO.
